US0D1010250S

(12) **United States Design Patent** (10) Patent No.: **US D1,010,250 S**
(45) Date of Patent: ** Jan. 2, 2024

(54) **STOP BARKING DEVICE**

(71) Applicant: **Shenzhen Hedasheng Trading Co., Ltd.**, Shenzhen (CN)

(72) Inventor: **Ji Mo**, Gaozhou (CN)

(73) Assignee: **Shenzhen Hedasheng Trading Co., Ltd.**

(**) Term: **15 Years**

(21) Appl. No.: **29/898,655**

(22) Filed: **Jul. 31, 2023**

(30) **Foreign Application Priority Data**

Jun. 28, 2023 (CN) 202330397978.6

(51) **LOC (14) Cl.** **30-99**

(52) **U.S. Cl.**

USPC **D30/199; D10/104.1**

(58) **Field of Classification Search**

USPC ..... D30/151-155, 144, 199, 160; 119/792-798, 850, 855-859, 863-865, 119/654, 905, 907, 815, 712, 802, 784, 119/769, 760, 776, 862, 908, 860, 119/719-721; 242/381.1-381.2, 385.4, 242/378.3, 376.1, 385.1, 916, 601, 570, 242/405, 404, 371, 223, 170, 388.1, 242/405.2, 377, 381.3, 381.6, 405.3, 242/388.6, 384.7, 382, 396.1, 404.1, 380; 362/108; 33/767, 769, 414; D12/400; D3/229, 230, 207, 208, 215; 40/1.5, 455, 40/640, 303; 206/63.3, 459.5, 702, 408; D6/515; D8/358, 360, 347, 360.1, 359, D8/356, DIG. 1; D24/145, 167, 186, 146, D24/169; D10/57, 72, 106.1, 104.1, D10/104.2, 109.2, 70, 97, 98, 78, 65; D20/28; 224/666, 678; 16/445; 283/74, 283/70; D11/232, 200, 216, 1, 2, 86, 87, D11/201, 206-210, 212-215, 218;

24/163 K, 122.3, 323, 702, 600.4-600.7, 24/163 R, 169-171, 173, 177-179, 191, 24/194, 195, 197, 200, 303, 616, 635, 24/313, 615, 3, 6, 3 K, 599.2, 96, 221, 24/237, 311, 312, 314, 321, 338, 339, 24/309; 428/3, 4; 54/76, 1, 71; 63/29.1, 63/3; 191/12.2 R, 12.4; D13/154, 153, D13/137.4, 155, 103, 168; D19/69, 67; 379/438; 446/26; 473/576; D22/140; 174/135; 439/504, 13, 501; D34/33; (Continued)

(57) **CLAIM**

The ornamental design for a stop barking device, as shown and described.

DESCRIPTION

FIG. 1 is a first perspective view of a stop barking device showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the stop barking device that form no part of the claimed design.

1 Claim, 8 Drawing Sheets
